BATTERY TERMINAL CONNECTOR

Orrin H. Thomas, Williamsport, Pa., assignor of fifty per cent to Joseph G. Saricks, Clearfield, Pa.

Application September 24, 1951, Serial No. 247,938

1 Claim. (Cl. 339—231)

1

This invention relates to a terminal connector and more particularly to a device of the kind adapted for use with the posts of a storage battery, and it consists in the constructions, arrangements and combinations herein described and claimed.

The main objection to present day battery terminal connectors is that they lock or freeze to the battery post. This is because when the connector is placed on the post and the nut tightened to draw the clamping member around the post, the clamping member metal is forced against the bolt body and the threads of the bolt causing a binding action between the clamp and the bolt. Furthermore this binding action prevents the clamping member from following the contour of the battery post and therefore impairs the connection and flow of electrical current between the battery post and terminal connector.

It is therefore an important object of the invention to provide a connector in which the clamping bolt cannot prevent the contacting portion of the connector from following the contour of the post and thus provide a better connection between the post and terminal connector. This works to a like advantage in the removal of the terminal connector from the battery post, for when the tightening bolt is backed away from its position against the clamping member, the clamping member will readily return to its original open position.

It is also an important object of the invention to provide a connector for storage battery posts wherein the clamping action is accomplished without the need for the clamping bolt to pass through apertured jaws of the clamp, thus reducing liability of corrosion between the jaws, post and the clamping bolt.

It is a further important object of the invention to provide a connector for storage battery posts wherein the post-engaging collar of the connector has a movable portion adapted to firmly grip a post positioned therein upon tightening of a bolt member, one end of which is in contacting engagement with said movable portion of the collar.

More specifically, it is an object of the invention to provide a connector in the form of a closed loop, one portion of which forms a rigid post-engaging jaw and including a movable jaw within the loop in opposed relation to the first jaw, the loop having a bolt threadedly engaged therein adapted to contact the movable jaw to draw said rigid jaw and press the movable jaw into forcible engagement with a post positioned

2

between said jaws, when said bolt is rotated in one direction.

Additional objects, advantages and features of invention will be apparent from the following description considered in conjunction with the accompanying drawing, forming a part of this specification.

In the drawing—

Figure 1 is a top plan view of the connector in operative engagement with a battery post.

Figure 2 is a side elevation of the connector.

Figure 3 is a longitudinal section on the line 3—3 of Figure 5.

Figure 4 is an end view of the connector.

Figure 5 is a cross section on the line 5—5 of Figure 4, and

Figure 6 is a cross section similar to Figure 5, illustrating a modification of the connector.

There is illustrated a connector generally indicated by the reference character 10, molded as an integral closed loop member formed from any suitable metal. The connector comprises an annular body 11 having a rigid jaw 12 constituting a portion of the closed loop member and a movable jaw 13 within the loop and arranged in opposed relation to the jaw 12, the annular body further having a tapered opening 14 for receiving a battery post 15, as shown in Figure 1.

The rigid jaw 12 is contiguous with a right angularly disposed wall 16 which in turn is integral with a wall 17, the latter lying in a plane parallel to the rigid jaw 12, said wall 17 being molded as an integral part of the annular body 11, thus forming the closed loop.

The movable jaw 13 is formed as an integral extension of the annular member 11, arranged in parallel relation to the fixed jaw 12, but spaced therefrom, as well as from the wall 17. It should be noted that the juncture of the wall 17 with the annular member 11 is at a point approximately medially of the longitudinal axis of the tapered opening 14 of the annular member 11, as indicated at 18, which allows ample movement of the movable jaw 13 about the circumference of a binding post for securing of the connector, without exerting excessive strain at the juncture 18.

In order that a conductor cable (not shown) may be secured to the connector 10, a collar or sleeve 19 is integrally formed with the annular member 11 extending rearwardly therefrom. A cable may be inserted into the passage 20 of the sleeve and secured by means of a bolt 21 threadedly engaged with a nut 22 embedded in a boss

23 of the sleeve. It will be seen that the bolt 21 enters the passage 20 at right angles thereto and obviously when the bolt 21 is moved inwardly, the inner end of the bolt will impinge upon a cable within the sleeve.

The wall 17 of the closed loop has molded therein a nut 24, the threaded opening of which lies in a plane in alignment at right angles to the movable jaw 13, and to effect movement of the jaw into clamping engagement with a battery post, a threaded bolt 25 is engaged with the threaded opening of the nut. It will be seen that upon inward movement of the bolt 25 into engagement with the adjacent face of the jaw 13, which it will be noted is at a point spaced from the center of the opening 14 of the annular member the latter will be moved in a direction circumferentially of a post and at the same time a pulling force upon the jaw 12 will be exerted by virtue of the wall 16, so that the walls of the tapered opening 14 will be forcibly drawn about the post 15, as indicated in Figure 1.

In the modified form of the connector shown in Figure 6 the parts are identical with the construction just described, except for the addition of a tension and reinforcing spring, and the elimination of the nut 24. The corresponding elements are identified by primed reference characters. Where it may be desirable to increase the resilience or spring tension of the movable jaw 13', a flat steel spring 26 may be embedded directly in the body of the jaw, the spring being so shaped as to extend partially around the annular member 11' and through the wall 17'. The nut 24 of the first form is elimi-

nated and in its stead the spring 26 is formed with a threaded opening 27 for reception of the bolt 25'. In addition to increasing the resilience of the jaw 13, the juncture 18' between the annular member 11' and the wall 17' is reinforced.

While I have shown and described preferred forms of the connector, this is by way of illustration only, and I consider as my own all such modifications in construction as fairly fall within the scope of the appended claim.

I claim:

A battery terminal comprising a split ring having parallel jaws extended therefrom, one jaw extending across the split of the ring and having a return bend parallel to the other jaw and being joined to the split ring at a point tangentially to the latter jaw, said other jaw being free at its one end, screw means threaded through the return bend to move the free jaw toward the first mentioned jaw, and said split ring further having means for connection of a battery cable.
